(57) **CLAIM**

The ornamental design for a remote control, as shown and described.

DESCRIPTION

FIG. 1 is a perspective view of the remote control of the present invention;
FIG. 2 is a front elevational view of the remote control of FIG. 1;
FIG. 3 is a rear elevational view of the remote control of FIG. 1;
FIG. 4 is a left side elevational view of the remote control of FIG. 1;
FIG. 5 is a right side elevational view of the remote control of FIG. 1;
FIG. 6 is a top view of the remote control of FIG. 1; and,
FIG. 7 is a bottom view of the remote control of FIG. 1.
The portions drawn in broken lines are for illustrative purposes only and form no part of the claimed design.
